UNITED STATES PATENT OFFICE.

WILLIAM G. CLARK, OF ALTOONA, PENNSYLVANIA.

SANITARY BAR.

No. 865,359.

Specification of Letters Patent.

Patented Sept. 10, 1907.

Application filed April 25, 1907. Serial No. 370,278.

To all whom it may concern:

Be it known that I, WILLIAM G. CLARK, a citizen of the United States, residing at Altoona, in the county of Blair and State of Pennsylvania, have invented certain new and useful improvements in Sanitary Bars, of which the following is a specification.

This invention relates to an improvement in store furniture, and has special reference to what may be characterized as a sanitary bar designed to replace the old style bar or bar counter commonly used in restaurants or bar rooms.

To this end the invention contemplates a simple, practical and thoroughly sanitary bar structure wherein a clear and unobstructed space is provided entirely under the bar or bar counter, which at the same time exposes every part of the bar fixture to view for purposes of inspection and cleaning.

In the above connection the invention also contemplates a simple and practical mounting of parts comprising a bar or bar counter which insures an absence of the uncleanliness and other well known objections to the old style wooden bars consisting of a counter top and solid paneling closely built up from the floor to said counter top and completely inclosing the back of the bar from view.

A further object of the invention is to provide a bar construction permitting of a great degree of ornamentation so as to present to the eye a bar or bar counter of an exceedingly attractive ornamental design.

With these and many other objects in view, which will more readily appear as the nature of the invention is better understood, the same consists in the novel construction, combination, and arrangement of parts, hereinafter more fully described, illustrated, and claimed.

The essential features of the invention involved in carrying out the objects above indicated are necessarily susceptible to a variety of structural changes without departing from the scope of the invention, but a preferred embodiment thereof is shown in the accompanying drawings, in which—

Figure 1 is a front elevation of a sanitary bar or bar counter constructed in accordance with the present invention. Fig. 2 is a rear elevation of the same. Fig. 3 is a top plan view of the bar or bar counter. Fig. 4 is a vertical transverse sectional view on the line 4—4 of Fig. 3.

Like references designate corresponding parts in the several figures of the drawings.

In carrying out the present invention, the improved bar embodies in its general organization a series of upright regularly spaced supporting pedestals 1, a counter top 2, an inside work table 3, and ornamental grille sections 4 arranged in the form of panels between the separate pedestals and providing open work paneling

effect for the bar, which is disposed a material distance above the plane of the floor in the manner to be presently explained.

It is the intention of the present invention to provide a bar structure constructed of cast iron throughout with the single exception of the renewable counter top 2, thereby admitting of a high degree of finishing by means of painting and enameling.

The upright supporting pedestals 1 are arranged in any desired number, according to the length of the room to be fenced off, but are preferably arranged in regular spaced relation to maintain a proper ornamental effect as well as to provide for the effective support of the various parts and fixtures carried by the bar. The said pedestals are duplicates in construction and each consists of a semi-tubular casting formed at its lower end with an integral widened foot piece 5 preferably provided with the attaching flanges 6 adapted to receive suitable fastenings for readily securing the pedestals 7 to the floor. Above its widened foot piece 5 each supporting pedestal is in the form of an upright column and at its upper extremity is provided with an inwardly extending braced horizontal top bracket 7 of a double flanged formation and whose flanges are adapted to receive the screws or equivalent fastenings 8 for fastening in position the wooden or equivalent counter top 2. This counter top 2 is secured to the top bracket 7 of the entire series of supporting pedestals and is preferably provided at its front edge with an ornamental front rail 10, said counter top and its rail constituting the part of the bar over which the liquor or refreshments are served by the attendant.

In addition to the horizontal top bracket 7, each of the metallic supporting pedestals 1 is provided at a point intermediate the upper and lower ends of the pedestals with inwardly extending horizontal table brackets 11 of greater length and projection than the top bracket 7 supporting the counter top 2.

The brackets 11 of the several supporting pedestals 1 are preferably of a doubled flanged formation so as to provide for the secure attachment thereto of the different sections of the inside work table 3 which may be fastened to the said table brackets by any suitable or approved fastening means or device. The said inside work table 3 is made up of a number of individual metal tubs or sinks, certain of which are provided with the plumbing fixtures commonly employed in connection with bars or bar counters, and one or more of the said tubs or zincs, additionally designated by the reference letter B, may be constructed to provide what may be characterized as a combined bottle holder and cooler, the same being of tub formation having a main central ice compartment 15 and a plurality of individual bottle holding cells 16 surrounding the said ice compartment 15 and providing means for holding the bottles in convenient position for use and also in sufficient proximity

to the ice to maintain the contents cool. There is also associated with and supported by the bar structure a dispensing apparatus embodying in its organization the coil box 17, the draw off spigots 18 carried by said box, and a spigot drip tub 19. The coil box 17 is supported from the counter top 2 and is covered at its open upper side by the strainer plate 20 seated flush within the counter top, while the drip tub 19 is arranged in the vertical plane of, and below the draw-off spigots 18 and is arranged for support upon the table brackets 11 of the centrally arranged pedestals.

Another tub designated by the reference letter B, may be characterized as a combined rinse tub and draining surface for glasses. The tub B is constructed so as to admit air underneath the glasses as they are placed bottom up on the silex drain boards B³ of said tub. It will thus be seen that the various necessary accessories of the bar and its serving apparatus are supported on and carried by the same structural parts, and in order to complete the bar and add to the finish and appearance thereof there are employed the ornamental grille sections 4 spaced between the supporting pedestals and provided at their ends with attaching ears 22 which are bolted or otherwise suitably fastened to the holding lugs 23 projected from the sides of the supporting pedestals. Any section of the grille may be arranged to act as a gate to admit the attendant to his place behind the bar by using lugs on the columns and corresponding lugs on the grille as hinges. This arrangement consolidates the structural elements and also adds to its ornamental arrangement. The grille section 4 is constructed with a supporting lug 24 designed to support a glass guard plate 25. This plate is constructed so that its removal or replacement in no way affects the ornamental design and its use prevents the throwing of cigar refuse through the grille work to the work board of the bar.

A distinctive feature of the invention resides in arranging the grille sections close up to the under side 40 of the counter top at the front thereof and leaving a clear wide unobstructed space between the bottom edges of the grille sections and the floor so that there is an opening beneath the bar to admit of thorough cleaning and to absolutely prevent the accumulation 45 of filth, etc., which is common to the usual bar.

From the foregoing, it is thought that the essential features of the general bar structure will be fully understood, and it will be noted that various changes in the form, proportion, and minor details of construction may be resorted to without departing from the spirit or 50 sacrificing any of the advantages of the invention.

I claim:

1. A bar comprising a plurality of supporting pedestals, a counter top supported from the upper end of said pedestals, a work table supported at the inner sides of 55 the pedestals below the counter top, and a fencing carried by the pedestals beneath the counter top and spaced a distance above the floor upon which the pedestals rest.

2. A bar comprising a series of upright spaced supporting pedestals provided with horizontal brackets, a counter 60 top carried by certain of the brackets, an inside work table carried by other brackets of the pedestals, and a fencing carried by the pedestals and arranged a distance above the lower ends of the latter.

3. A bar comprising a series of upright spaced supporting pedestals having inwardly extending horizontal brackets respectively at the top and at an intermediate point thereof, a counter top supported upon the uppermost brackets, a sectional work table carried upon the intermediate brackets, and grille sections secured to the pedestals in 70 a plane above the lower ends of the latter.

4. A bar comprising a plurality of metallic supporting pedestals provided at their upper ends and at intermediate points with inwardly extending horizontal brackets, a counter top fastened to the top brackets of the pedestals, a 75 sectional work table mounted on the intermediate brackets of the pedestals, and grille sections fastened to the pedestals in a plane above the lower ends of the latter.

5. A bar comprising a series of metallic supporting pedestals having widened foot pieces and provided at the 80 top and at an intermediate point with inwardly extending horizontal brackets respectively of different lengths, a counter top mounted on the top brackets of the pedestals, a sectional work table mounted on the longer intermediate brackets of the pedestals, and grille sections detachably 85 mounted on and between the pedestals in a plane above the lower end of the latter.

6. A bar comprising a series of supporting pedestals having a plurality of horizontal brackets, a counter, grille sections detachably mounted in the sections, and means for supporting glass guards immediately behind the grille sections.

In testimony whereof I hereunto affix my signature in the presence of two witnesses.

WILLIAM G. CLARK.
